UNITED STATES PATENT OFFICE.

LEE BAYER, OF WILLISVILLE, ILLINOIS.

SMOKE-CONSUMER.

1,063,320.

Specification of Letters Patent.

Patented June 3, 1913.

Application filed February 23, 1912. Serial No. 679,230.

To all whom it may concern:

Be it known that I, LEE BAYER, a citizen of the United States, residing at Willisville, in the county of Perry and State of Illinois, 5 have invented certain new and useful Improvements in Smoke-Consumers, of which the following is a specification.

This invention relates to smoke-consumers, and more particularly to that class 10 thereof in which the uncombined carbon is separated from the gases, the heavier deposits being deposited in a chamber and subsequently washed out therefrom, while the gases are either wholly or partly carried 15 back to the furnace to enhance the combustion.

The invention has for one of its objects 20 the provision of improved means whereby separation of the uncombined carbon is established in such a manner that practically all the waste material will be cleaned from the current of smoke so as that a practically clear coal gas may be saved for the purpose above stated.

25 The invention has furthermore for its object the provision of an apparatus of this kind in which the smoke will be screened, the screens being subjected to a wetting-down process which is preferably continuous 30 so that all material deposited on said screens will be washed away therefrom, and the device will remain in constant perfect operation.

The invention has also for its object the 35 provision of a series of catch-members or baffles disposed in successive tiers so that the air or smoke current will precipitate the uncombined carbon of the smoke against these members.

40 Further objects of the invention will hereinafter appear and be particularly defined in the claims.

The invention has been clearly illustrated 45 in the accompanying drawings, in which—

Figure 1 is a top view of a smoke-consumer embodying my invention. Fig. 2 is a side view thereof. Fig. 3 is a top view of the condensing chamber, the top being broken away. Fig. 4 is a longitudinal vertical section of the condensing chamber, and Fig. 5 is a cross section on line 5, 5 of Fig. 4.

50 Referring to the drawings, 10 denotes the chimney or stack of a furnace, having a damper 11 whereby the products of combustion may be permitted to pass out directly through the upper open end of the stack, or

they may be deflected toward the smoke-consuming or condensing apparatus, by a pipe 12 having at one end thereof a cover or trap 13 which may be opened for the 60 purpose of cleaning out that part of the apparatus. At its other extremity the pipe 12 is slightly contracted as at 13', and at this point it is surrounded by a casing 14 into the bottom of which a pipe 15 leads to 65 conduct exhaust steam into the annular chamber formed between the casing 14 and the pipe 15'. A valve 16 is provided to regulate the amount of steam injected.

The casing 14 is connected directly with 70 the precipitating or condensing chamber 17 which consists substantially of an inclosed box containing a series of spaced vertical screens 18 supported in any suitable manner and disposed beneath troughs 19 which 75 are adapted to contain water as supplied by a main pipe or trough 20. The latter extends longitudinally of the precipitating chamber, and the troughs 19 are in communication therewith. The flow of water 80 supplied to these troughs may be regulated by a valve 21 forming a part of the water supply pipe 22 which may receive its supply from any convenient source.

By referring to Fig. 4, it will be noted 85 that each of the troughs 19 has its marginal edges turned down to form side-sheds so that practically two streams of water flow over the opposite sides of each trough and serve for the purpose of wetting-down both 90 sides of each screen 18 interposed between the adjacent pair of side troughs 19, as clearly shown.

In order to prevent a direct current of smoke from finding its way above the 95 troughs 19 and screens 18, I provide a series of guards 23 so that any smoke tending to pass over the troughs 19 will be guided downwardly and in contact with the water running over the edges of the trough. 100

To the other end of the condensing chamber 17 is attached a fan casing 24 in which a fan 25 (constructed in any desired manner) may be rotated, as for instance by a shaft 26 and pulley 27 to which power may 105 be applied from any convenient source, it being understood that the casing 17 opens directly and centrally into the fan casing 24 which is provided with a discharge outlet.

110 From the foregoing construction it will be understood that the rotation of the fan 25

will tend to draw the product of combustion from the stack through the casing 17 in which latter they encounter the several screens where practically all the heavier elements are caught and retained and precipitated by the flow of water from the troughs 19 down into the bottom of the casing from whence they may be washed out through openings 29 provided near the bottom of the 10 casing and communicating with a waste pipe 30 also connected with the interior of the condensing chamber.

Doors 31 may be provided in the side of the casing to permit access to the interior 15 thereof for the purpose of cleaning out or renewing the screens.

In order to increase the efficiency of the apparatus as a soot-catcher, I provide on each of the screens a series of catch-members 20 or deflectors disposed in the direct line of travel of the smoke through the casing, the deflector bars of one screen being out of current line with the preceding one, so that even if some particles of the uncombined carbon 25 of the smoke should chance to pass through the wet screen, yet they will be caught or thrown against these bars; thus they are washed down by the water issuing from the trough disposed above that particular screen.

It therefore follows that the greater portion 30 of the carbon deposits will have been removed from the smoke current by the time it reaches the fan casing, but in order to clarify this current and to still further separate the gases from this carbon deposits, 35 means are provided whereby the air or smoke current issuing from the fan casing will be subjected to a washing and cleansing process, as for instance by a wash tank 32 in direct 40 communication with a pipe 33 leading from the discharge opening of the fan casing 24 to a point near the bottom of the tank 32. The latter contains a body of water W and is closed at its top by a cover 34 which is provided with an opening into which a pipe 35

projects so as to leave a space between the end thereof and the water body W. Any coarse matter will therefore be retained in this body of water and will gradually sink 50 to the bottom, while other matter of a lighter nature will, by the force of the current through the water-body, be projected into the pipe 35, the other end of which terminates near the bottom of the second washer 55 or cleansing chamber shown herein at 36 and also containing a body of water W' in which a quantity of glass-wool is placed. The top of the washer 36 is closed by a cover 37, and a pipe 38 leads from the upper air space of 60 the washer to the furnace, so that the now cleansed gas may be reconducted to the fire box of the furnace, and there aid in producing heat and combustion.

From the foregoing it will be seen that the fan mechanism described constitutes in reality a pump whereby the smoke will be drawn into the condensing chamber and then forced in the form of cleansed gases back into the furnace.

Inasmuch as it may be desirable to lead 70 the gases back into the chimney or stack, rather than into the furnace, I have provided a by-pass 39 connecting the gas pipe 38 with the stack 10, through which passage the gases may be deflected into the stack 75 by a damper or check plate 40 pivoted at 41 and adapted to divert the flow of gas to the stack or to the furnace, either partly or entirely, as controlled by a handle lever 42.

The particular purpose of the exhaust 80 steam in connection with my improved apparatus is: to dampen the products of combustion and to humidify the air or smoke to such an extent that the foreign matter and uncombined carbon contained in the smoke 85 will be rendered more or less heavy and thus have greater adhering tendency at the time when it encounters the several screens.

Many changes may be made in the particular construction and organization of several 90 of the component elements of my improved apparatus without departing from the spirit of the invention.

I claim:—

1. A smoke-consumer comprising a casing, 95 a series of vertical screens disposed therein, a trough disposed above and between adjacent screens and shedding water from its opposite sides against the adjacent faces of said screens, and a water supply for said troughs.

2. A smoke-consumer comprising a casing, a series of spaced vertical screens disposed therein, troughs disposed between the adjacent screens and supplying a stream of running water to both sides of each screen, and a water supply connected with all of said troughs.

3. A smoke-consumer comprising a casing, 110 a series of vertically disposed screens disposed therein, a series of troughs disposed above said screens for discharging water onto both faces thereof, and a water supply for said troughs, and a series of rods carried by each screen and intersecting the current of air passing thereto, the rods of the successive screens being disposed in different planes relatives to the direction of the air current.

In testimony whereof I affix my signature 120 in presence of two witnesses.

LEE BAYER.
